(57) CLAIM

The ornamental design for a necktie, as shown and described.

DESCRIPTION

FIG. 1 is a front perspective view of a necktie in accordance with the present invention.

FIG. 2 is a rear perspective view of the necktie of FIG. 1.

FIG. 3 is a top view of the necktie of FIG. 1.

FIG. 4 is a left side view of the necktie of FIG. 1.

FIG. 5 is a right side view of the necktie of FIG. 1; and,

FIG. 6 is a front view of the necktie shown in use.

The broken lines showing of a gentleman is for illustrative purposes only and forms no part of the claimed design.
